CONTINUOUS MOLD ALIGNMENT

Filed July 10, 1950

INVENTOR:

James Fernando Jordan

UNITED STATES PATENT OFFICE

2,601,615

CONTINUOUS MOLD ALIGNMENT

James Fernando Jordan, Huntington Park, Calif.

Application July 10, 1950, Serial No. 172,933

1 Claim. (Cl. 22—57.2)

1
My invention relates to the continuous casting of metal shapes in a water-cooled mold.

In order to satisfactorily operate a continuous mold, it has been found necessary to lubricate the outside surface of the cast shape, so that contact between said surface and the wall of said mold does not cause binding therebetween. While lubrication tends to prevent binding, it not only fails to prevent certain other effects arising from improper alignment of the cast shape within the mold, but it also interferes with the flow of radiant heat across the shrink gap lying between the shape and the mold. If contact between said surface and said mold takes place shortly after the casting skin first forms, said skin will be either torn or deformed, lubricant or no lubricant; furthermore, improper alignment introduces an uncertain heat-flow situation into the picture as the mold removes heat faster from those portions of the cast shape which lie closest to said mold. In short, lubrication is not a proper substitute for proper alignment between the cast shape and the mold.

My invention concerns my method of centering the cast shape within the mold, so that contact between said shape and said mold is eliminated, and so that skin tears and deformation are eliminated. Other objects will be apparent in the specification.

The conventional method of centering the cast shape within the mold consists of so withdrawing said cast shape out of said mold so that said shape is centered with respect the opening in the mold out thru which the cast shape emerges, the mold and cast shape being independently supported. Such alignment does not assure the absence of skin tear and distortion; for, alignment at the bottom opening of the mold does not assure alignment within the mold, and it is the alignment within the mold that is our major concern. Realizing this, some operators attempt to withdraw the cast shape out of the mold so that the casting axis—the axis of the mold—coincides with the axis of the cast shape—in other words, so that the mold and shape are coaxial. Even if it were possible to coaxially align the mold and the shape at the beginning of the operation, there is little chance that conventional means for withdrawing the cast shape out of the mold could long maintain this coaxial relationship, due to the difficulties surrounding the precise handling of a red hot, heavy object, such as an ingot. Furthermore, with the mold and shape independently supported, so that the mold is permanently fixed while the cast shape is moveable in accordance with the mode of operation of the withdrawing means positioned well below the bottom of the mold, the upper end of the cast shape must inevitably move around within said mold as slight changes in the action of the withdrawing means

2
are reflected in movements at the top of the cast shape. Nor would it help the situation to so arrange the withdrawal so that movements of the top of the cast shape were slight, for if the top 5 of the shape moves at all, however slightly, the freshly-formed skin of the casting will be distorted, crushed, or worse. When the skin of the casting first forms and draws away from the wall of the mold, the clearance between skin and wall 10 is at first only a few thousandths of an inch and said skin is very weak and brittle, so that if a movement of the cast shape presses the freshly-formed skin against the wall of the mold, said skin is easily deformed, and the skin will likely be torn. When it is remembered that these troubles 15 can develop when an ingot weighing tons—being, perhaps, twenty or thirty feet long and supported by withdrawing means position ten feet or more from the point where said skin is first forming—20 moves only a few thousandths of an inch at its top, it will be appreciated that even a slight wobble will at once crush the freshly-formed skin.

I have solved this problem by mounting the mold so that it is free to move with the cast 25 shape as said shape moves in a horizontal or tipping manner, and then I align said mold with said cast shape at at least two positions along the cast shape, the means of such alignment being arranged so that movements on the part of the 30 cast shape will be immediately reflected in corresponding movements on the part of the mold.

In the figure, I show mold 8 being cooled by water 11 flowing thru jacket arrangement 9. Incoming molten metal 5 enters mold 8 to form pool 35 10, surface 7 being the surface of said pool 10. Mold 8 is shown positioned on platform 14 thru the instrumentality of springs 13, said springs 13 being arranged so that they permit horizontal or tipping movements of the part of mold 8, while 40 preventing the downward movement of mold 8. As pool 10 solidifies at interface 12 to form shape 19, shrink gap 17 forms between shape 19 and mold 8, gap 17 being formed by the contraction of the metal, by the taper of mold 8, or both. 45 For the purpose of clearly picturing the action of my arrangement, the width of gap 17 between mold 8 and shape 19 has been exaggerated. As pool 10 solidifies to form shape 19, withdrawing means 4 grasp shape 19 and move it out of mold 50 8 in direction 20 at a rate in keeping with the rate of solidification.

I align mold 8 with shape 19 by, first, centering shape 19 within mold 8 by means of a plurality of bearings 16, the adjustment being made 55 with adjustment screws 18 as the relative position of mold 8 and shape 19 is observed thru viewing holes 15, and then I center shape 19 within mold 8 by means of a plurality of bearings 116, the adjustment being made with adjustment screws 118. Bearing means 16 and 116

being supported by mold 8, horizontal or tipping movements on the part of shape 19 will be immediately and quantitatively reflected in paralleling movements by mold 8, resulting in the continued maintenance of the cast shape in a centered, out-of-contact position with respect to mold 8.

Bearings 16 and 116 are any type of bearings which are capable of transmitting the movements of shape 19 to mold 8; that is, they may be friction-type bearings—as shown in the figure, or they may be live bearings—ball bearings or rollers, for example. Furthermore, the force exerted on bearings 16 and 116 may be transmitted to mold 8 thru the instrumentality of springs (not shown) that lie between said bearings 16 and 116 and adjustment screws 18 and 118, the tension on said springs being adjusted so that said tension maintains the centered relationship between mold 8 and shape 19. When casting a round shape 19, at least three bearings should be employed at each aligning position, as in the figure; when casting a square or rectangular shape 19, at least four bearings should be positioned around the cast shape—that is, at least one bearing being positioned on each side of the shape at each aligning position.

Suspension means 13 have the function of supporting mold 8 while permitting mold 8 such horizontal or tipping movements as may be transmitted by bearings 16 and 116. In the figure, means 13 are shown as springs under compression; however, mold 8 may be hung by springs instead of resting upon same—the advantage of the arrangement shown is that it keeps the upper, open end of mold 8 clear, so as to facilitate the pouring operation.

Another type of continuous mold is available for casting a continuous shape. My application, Serial No. 87,048, filed on April 23, 1951, now matured into Patent No. 2,553,921, disclosed such a mold. The mold of 87,048 employs the blind riser principle, said mold being suspended over and dipping into the molten metal that is to be cast, so that said molten metal flows into said mold by flowing up thru the refractory opening at the immersed end of the mold, the solidified shape being withdrawn out of the opening in the top of said mold by withdrawing means positioned above said mold. By turning the figure upside down, the use of my present invention in a mold of the type of 87,048 may be seen, except for the refractory arrangements on the immersed end of the mold—arrangements which have no bearing in the present invention.

Whatever the spring supporting arrangement may be, the water-jacket of the mold must be connected to its source of water supply by means of rubber pipe, so that the water connections do not interfere with the action of spring means 13.

Various arrangements may be employed to align the mold and shape. In the figure, the metal tube that forms mold 8 is extended beyond the water-cooled section, so as to facilitate the operation; however, the water-cooled section may be arranged so that the bearings are positioned therein.

Having now described my invention, I wish it to be understood that my invention is not to be limited to the specific form or arrangement of parts hereinbefore disclosed, except insofar as such limitations are specified in the appended claim.

I claim as my invention:

In a continuous casting apparatus having an open-ended mold, and means for withdrawing out of said mold metal solidified within said mold, the combination therewith of elastic means for supporting said mold, said elastic means being positioned between said mold and a rigid support, and mold aligning means for coaxially aligning said mold with the solidified shape being formed within and withdrawn from said mold, said mold aligning means being supported by said mold and being positioned with respect to said solidified shape by bearing means which contact said solidified shape, so that substantially all horizontal movements of said cast shape are imparted to said mold by said aligning means.
